MACHINE FOR TREATING FABRIC

Elery L. Smith, Melrose, Mass., and Harold H. Belcher, Philadelphia, Pa., assignors to The Philadelphia Drying Machinery Company, Philadelphia, Pa., a corporation of Pennsylvania

Application October 24, 1929, Serial No. 402,186
Renewed May 12, 1933

4 Claims. (Cl. 34—48)

This invention relates to the treatment of fabrics, and more particularly to the drying and carbonizing of cloths. Such drying and carbonizing treatment is applied in the textile art to 5 woolen cloth that has previously been treated with dilute acid or the like. The drying concentrates the dilute acid in the cloth, so that under the high carbonizing heat the concentrated acid chars and virtually destroys any vegetable or cel- 10 lulose material in the cloth,—leaving any carbon residue thereof so friable as to be easily eliminated by beating, crushing, or the like after the carbonizing. In this way materials such as burrs, straw, wood splinters, etc., that have been carried 15 through previous operations with the wool, may be gotten rid of without tedious and costly hand burling; also, cotton threads or the like purposely woven into woolen cloth may be eliminated, so as to leave the cloth with an open texture, or even 20 an open pattern effect.

The acid agents commonly used in the carbonizing process are sulphuric acid and aluminum chloride. Their action on cellulosic materials is very much the same; but the aluminum chloride 25 has less effect on the wool, and is therefore sometimes preferred where sulphuric acid might produce un-uniform results. However, aluminum chloride is considerably more expensive, and produces much more corrosion of equipment in the 30 plant where it is used; so that it is a considerable advantage to be able to use sulphuric acid rather than aluminum chloride.

To avoid injury to the cloth, it is important 35 that it be well dried before being subjected to the fairly high carbonizing heat; and this is especially true of cloth containing any silk, since a material amount of moisture in such cloth would cause carbonization of the silk by the heat necessary to carbonize the cellulosic matter. It 40 is also desirable to effect the drying of the cloth in stages of increasing temperature, or at temperatures progressively increasing as the amount of moisture in the cloth decreases, rather than by prolonged exposure at the highest drying tem- 45 perature; for it is found that as the amount of moisture in the cloth grows less and less, it can stand higher and higher temperatures without injury. Notwithstanding all these precautions, however, carbonizing processes have not heretofore given satisfactory results: on the contrary, 50 the cloth treated is often marred by cloudiness, spots, streaks, or other variations from strict uniformity of color or appearance, and there are apt to be differences in color between its opposite 55 sides or faces.

We have discovered how these disadvantages of prior practice can be obviated, and have provided a new drying and carbonizing outfit or machine for properly treating cloth by the carbonizing process. The success and the essential novelty of

our invention will be better understood from our explanation of what is involved in drying and carbonizing cloth, and in the action of the outfit described hereinafter.

In the ordinary drying of cloth, where only 5 moisture is present, temporary unevenness in drying has no lasting ill effect on the goods,—at least when not extreme or greatly prolonged. In a drying and carbonizing process, however, where the goods initially contain dilute acid, the case 10 is different.

When some portions or facial areas of cloth that contains dilute acid dry faster than others, the dilute acid in the slow places tends to diffuse 15 into the faster drying places, under capillary action, so as to equalize the moisture content. As a result, more of the total water in the cloth is evaporated in the fast-drying portions or areas, and hence more of the concentrated acid is finally left in them: i. e., the concentrated acid is so 20 unevenly distributed in the dry cloth that some places have an excess of this acid, while others have a deficiency. When such cloth is carbonized, deficiency of concentrated acid may cause imperfect or incomplete carbonization of cellulosic 25 material in the corresponding portions or areas. Moreover, in cloth that has been dyed before drying and carbonizing, the uneven distribution of acid may cause correspondingly varying chemical 30 action on the dyes and on the goods; while in cloth that has not been dyed before drying and carbonizing, the unevenly distributed acid will produce correspondingly varying effects on the wool, or on the grease therein, so that when such 35 goods are subsequently dyed, they will take the dye unevenly, and will hence appear uneven or "shaded".

In a word, it is of very great importance to dry the cloth thoroughly and uniformly throughout its entire length and width before it is sub- 40 jected to the carbonizing heat or baking.

In our outfit or machine hereinafter described, these difficulties are practically overcome by distribution of the drying medium to act more uniformly on the cloth than heretofore, especially 45 as between its opposite sides or faces, which gives a more uniform distribution of concentrated acid in the cloth and thus equalizes the effects of the acid, particularly in the final stages of drying and carbonizing heat. This uniformity in the distribution of the concentrated acid also makes it generally feasible to use sulphuric acid in the 50 process, instead of the costlier and more corrosive aluminum chloride. We also aim to provide for maintaining the essential differing tempera- 55 tures effectively in different parts of the apparatus. Various other features and advantages of the invention will appear from the following description of a species of our outfit or machine, and from the drawings.

The invention is illustrated in a convenient form by the drawings accompanying, and forming part of, this specification; although it will be appreciated such drawings are purely illustrative or by way of enabling said invention to be clearly understood.

Fig. I is a side elevation, with parts broken away and in section to better disclose underlying features, of a roller-drying and carbonizing machine embodying the present invention.

Fig. II is a top plan view of the same; and.

Fig. III is a cross-sectional view, taken as indicated by the lines and arrows III-III on Figs. I and II.

15 Referring more in detail to the drawings, the equipment illustrated comprises an inclosure 1 of appropriate construction which is divided by a main partition 2 to provide a "drying" section comprehensively designated 3, and a "carbonizing" section similarly characterized as 4. The equipment, or, as hereinafter more suitably termed, machine shown consists of a conventionally constructed inclosure 1 including side walls 5, end walls 6, a roof of successive "peaks" 7 over the drying section 3, a flat roof 8 over the carbonizing section 4, and a floor 9.

The drying section 3 is sub-divided by vertical partitions 10 into a number of inter-connected compartments 11, respectively allocated to, and corresponding in number with, the succession of peaks 7 aforesaid. While it is to be noted, the partitions 10 extend from the inclosure floor 9 to the underside of the "gutters" 12 intervening the roof peaks 7, yet communication is afforded between the respective compartments 11 by way of openings 13 in the partitions 10. Auxiliary partitions 14, in turn, medially separate the peaks 7 and compartments 11 into what may be conveniently designated flow-and-return passageways for the treating or drying medium; said partitions 14 extending downwardly from the ridges 15 of the peaks 7 to within a distance from the floor 9. Each auxiliary partition 14, in that portion which divides the peak 7, is apertured and fitted with a housing 16 for reception of a vertically rotative fan 17; all of said fans being supported by a common shaft 18, journaled in bearings 19 conveniently mounted in the gutters 12, hereinbefore referred to, along the longitudinal center line of the machine. This shaft 18 is provided with a suitable drive 20, at one end, whereby it is operatively connected with any convenient source of power such as a motor 21, mounted on the roof 8 of the carbonizing section 1.

A heater unit 22 is positioned preferably, although not essentially, in the sub-division of each compartment 11 on the delivery side of the associated fan 17, and conveniently consists of a bank of coils through which steam—for example—is continuously circulated. The several heater units 22 may be independently controlled so that differing temperatures can be maintained in the successive drying compartments 11.

Material M, previously immersed in a saturating tank and subsequently passed through suitable means to remove the excess fluid, is passed over a guide roller 23 at the feeding-in end of the inclosure 1, through an entry opening 24, and trained about an upper series of driven-rollers 25 with an associated lower series of idlers 26, in the successive drying compartments 11, as well as correspondingly through the carbonizing section 4. The upper series of driven-rolls 25

are rotated by means of bevel gears 27 from a common line shaft 28, in turn co-ordinated with any suitable source of power.

Attention is now directed to the carbonizing section 4 in which, it will be observed, the heater units or steam coils 29 are differently located: they consist of sinuously disposed pipes arranged in vertical planes between the correspondingly advancing runs of the material M, as will be readily understood by those acquainted with this art. 10

Fresh air is admitted to the carbonizing section 4 by way of an inlet 30, in the lower part of the end wall 6 of said section, and provision is made for passing or diverting a variable quantity of air from the carbonizing section 4 into 15 the adjoining compartment 11 of the drying section 3. Such air diverting means, conveniently, comprises an adjustable damper 31 located in the upper part of the main partition 2, hereinbefore referred to. Attention is directed to 20 the fact that air entering the carbonizing section 4 is not re-circulated, by providing fans for such purpose, but it is supplied more in the nature of a constant flow, with controllable diversion therefrom. Fresh air, in variable quantity, may also be admitted to the drying section 3, by way of an inlet 32 in one of the side walls 5, under control of an adjustable damper 33, to assist in replenishing the moisture-laden atmosphere exhausting therefrom by way of an 30 outlet 34, in the leading peak 7.

Having outlined the structural features of our novel drying-carbonizing machine, the operation thereof may be briefly set forth as follows. Air entering the drying section 3 from the carbonizing section 4 by way of the damper controlled opening 35—Fig. I—is re-heated and re-circulated successively in the several drier compartments 11, flowing from one to the other through the openings 13 connecting the same. As shown, the heating means 22 traversed by the air in the circuit of each drier compartment 11 or pair of passages is substantially out of radiating proximity to the runs of cloth M, so that the moisture is mainly evaporated from the cloth by the circulating heated air, rather than by radiant heat. The drying medium, or heated air, thus travels forwardly and absorbs more and more moisture from the material M, counter-advancing, as indicated by the arrows thereon, until it reaches the first or entering compartment 11, where the exhaust outlet 34 is located. The vertically rotating fans 17 re-circulate the heated air in each of the drying compartments 11, which causes said air to pass upward and downward, in a vertical direction, between the “passes” or runs of the material M, as indicated by the arcuate flow-indicating arrows on Figs. I and III. This re-circulation of the drying medium ensures a much more uniform drying of the material M, throughout its entire length, by alternate action on both faces of said material during progress through the suction and delivery portions of the compartments 11, as will be clearly apparent by examination of Fig. I, more particularly. The drying process is also accomplished without any tendency to form creases and wrinkles, which objectionable tendency more or less obtains in analogous outfits where the air currents are usually blown into the material from the sides thereof, said air currents thus impinging the edges of the material and flowing transversely thereacross. At this juncture it is well to note that the lower rollers or idlers 28 in the suction portions of the drying compartments 11 are arranged in staggering or stepped relation from the 75

floor 9 of the inclosure 1, upwardly, which arrangement we find most effective in distributing the air currents uniformly across and throughout the passes or runs of the material M, as indicated by the associated arrows. On the other hand, the idlers 26 in the air delivery portions of the drying compartments 11 are preferably located in parallelism in a horizontal plane, and spaced above the heater units 22. Incidentally, the carbonizing section 4 of our improved machine is in effect a continuation of the drying section 3, separated only by the main partition 2 so that a high baking temperature is always maintained.

While we have herein disclosed a desirable form of our invention, it is to be distinctly understood the same is purely exemplary, and that variations in size, shape, proportion, and the relative location of the respective details may be resorted to without departure from the scope of the following claims.

Having thus described our invention, what we claim is:

1. An apparatus for the improved carbonization treatment of cloth, after saturation according to the known process, by drying and baking; said apparatus comprising an enclosure and a partition dividing it into carbonizing and drying sections, with communication between them; rolls in said enclosure for the guidance and passage of the cloth therethrough in a zig-zag series of runs; heating means for the air in the carbonizing section; partitions in the drying section, amongst and substantially parallel with the cloth runs, extending between opposite walls of the drying section from one of said walls substantially to adjacent the rolls near the opposite wall, and forming a series of drying compartments, intercommunicating substantially adjacent the last mentioned wall; intermediate partitions in said drying compartments, amongst and substantially parallel with the cloth runs, dividing the compartments into adjacent air-flow passages, with intercommunication substantially adjacent the aforesaid opposite drying section walls; rotary blower fans in the drying compartments for circulating and recirculating the air repeatedly through the passages of each drying compartment, in opposite directions between and against the cloth runs in their adjacent passages; and heating means in the path of the air from the cloth runs in one of the adjacent passages to those in the other.
2. An apparatus for the improved carbonization treatment of cloth, after saturation according to the known process, by drying and baking; said apparatus comprising an enclosure and a partition dividing it into carbonizing and drying sections, with communication between them substantially at the top of the enclosure; upper and lower rolls in said enclosure for the guidance and passage of the cloth therethrough in a series of up and down runs; heating means for the air in the carbonizing section; upright partitions in the drying section extending from the floor of the enclosure to adjacent certain of said upper rolls and forming a series of drying compartments, intercommunicating substantially at their upper ends; intermediate upright partitions in said drying compartments, extending downward from adjacent certain of the upper rolls between adjacent cloth runs, and dividing the compartments into adjacent up and down air-flow passages, with intercommunication substantially at top and bottom of the compartments; rotary blower fans in the drying compartments for cir-
3. An apparatus for the improved carbonization treatment of cloth, after saturation according to the known process, by drying and baking; said apparatus comprising an enclosure and a partition dividing it into carbonizing and drying sections, with communication between them substantially at the top of the enclosure; upper and lower rolls in said enclosure for the guidance and passage of the cloth therethrough in a series of up and down runs; heating means for the air in the carbonizing section; upright partitions in the drying section extending from the floor of the enclosure to adjacent certain of said upper rolls and forming a series of drying compartments, intercommunicating substantially at their upper ends; intermediate upright partitions in said drying compartments, extending downward from adjacent certain of the upper rolls between adjacent cloth runs, and dividing the compartments into adjacent up and down air-flow passages, with intercommunication substantially at top and bottom of the compartments; rotary blower fans in the drying compartments for cir-
4. An apparatus for the improved carbonization treatment of cloth, after saturation, by drying and baking; said apparatus comprising enclosed drying and carbonizing sections, the former including a plurality of intercommunicating drying compartments with heating means therein for the drying air, and the latter also including heating means, for baking the dried cloth; means for the guidance and passage of the moist cloth through the drying compartments in zig-zag series of runs, and for the guidance and passage of the dried cloth through the carbonizing section; partitions in said drying compartments, amongst and substantially parallel with the cloths runs, dividing each compartment into adjacent air-flow passages, intercommunicating substantially at opposite ends of the compartment; and blowing means at each compartment for circulating and recirculating the air therein repeatedly in a circuit over its heating means and through its passages, blowing substantially in the line of the cloth runs, but in opposite directions in said passages and against opposite sides of the cloth therein; so that the opposite faces and all portions of the cloth are dried substantially alike in each drying compartment and in this manner fully dried and brought to uniform condition in the drying section, assuring uniform effects on the cloth in the carbonizing section, and on its coloring from dye.
